UNITED STATES PATENT OFFICE.

GEORGE BINET DOREY, OF EVANSTON, ILLINOIS, ASSIGNOR TO ENTERPRISE RAILWAY/ EQUIPMENT COMPANY, OF CHICAGO, ILLINOIS, A CORPORATION OF ILLINOIS.

DUMP CAR.

Application filed May 25, 1925. Serial No. 32,591.

This invention relates to improvements in dump cars.

An object of this invention is to improve the construction of dump cars having discharge openings adapted to discharge the contents of the car adjacent the rails whereby flooding of the rails will be obviated.

Another object of the invention is to provide a car which will deposit ballast either centrally between the rails or to either side thereof as desired, and to provide means for positively controlling the flow of the ballast.

A more specific object of the invention is to provide a V-shaped hopper construction having a discharge door hinged adjacent the apex thereof and movable downwardly to an inclined position, in conjunction with means arranged to restrict the flow of the load until such time as the discharge door begins to assume a downwardly inclined position, and to provide an increased expanse of supporting portions movable from under the load to induce a ready flow of the material.

The invention further consists in the improvements in the parts, and in the novel combination of the parts and devices herein shown, described, and claimed.

In the drawings forming a part of this specification, Figure 1 is a top plan view of the hopper portion of a car showing my improvements in connection therewith. Figure 2 is a vertical sectional view of the lower portion of the car taken on a line corresponding substantially to the line 2—2 of Figure 1, said view showing the center doors and one of the side doors in open position. Figure 3 is a vertical, longitudinal sectional view taken through one of the hopper sections on a line corresponding substantially to the line 3—3 of Figure 2. Figure 4 is a fractional transverse sectional view through a portion of the car, showing the dumping doors in position as the discharge of the load commences. Figure 5 is a diagrammatical view, somewhat similar to Figure 4, showing the doors in position under normal ballasting operations.

In said drawings A—A denote the side walls of the car including side sheets 10, stakes 11, and reinforcing angle shaped bulb members 12 disposed along the margins of sheets 10 and secured thereto; B indicates the center sill construction, comprising a plurality of channels 13—13 and a plate 14 forming a girder-like structure; and C—C denote the lower portions of the sloping end walls

of the car, whereby lading is directed to the hopper sections from the adjacent flat floor, or convertible sloping floor section.

Intermediate the sloping floors C the car is provided with a hopper construction which includes four V-shaped hoppers D, longitudinally arranged in pairs on each side of the center sill, the hoppers being separated from each other longitudinally of the car by a transversely extending crossbeam structure E. As most clearly shown in Figure 2, each hopper section D includes an outer downwardly and inwardly inclined side hopper sheet 15, secured to the adjacent side wall of the car as indicated at 16, and is suitably braced and rigidified at its lower margin by means of an angle member 17. The opposite side of each hopper section D includes an inner downwardly and outwardly inclined hopper sheet 18, the hopper sheets 18 for each pair of transversely aligned hoppers being preferably in the form of a unitary structure carried by the center sill B, and suitably rigidified longitudinally at the lower margins by means of angle members 19, said sheets 18 being also connected to the center sills 13—13 by means of brackets 20.

Each hopper section D is also provided with wall portions at each end thereof, each wall 21 adjacent the related sloping end C preferably being an integral portion of the sloping end, and being connected therewith by a bent portion as indicated at 22. The inner end portion of each hopper section D, adjacent the cross-beam structure E, is preferably formed by a plate having oppositely disposed sloping sides 23—23 and lower vertically depending portions 24—24 of triangular shape. The plate providing the sloping walls 23, and vertical portions 24, is preferably of inverted V-shape and adapted to straddle, and be carried by a transversely extending beam 25, extending above the center sill from side to side of the car, as best shown in Figure 3.

The remaining portion of each hopper bottom section D is formed by movable closing means consisting of doors F and G, the doors F being hinged adjacent their upper edges to the respective sloping floors 15 and 18, adjacent their lower margins, and the doors G being hinged adjacent the apex of the hopper upon a longitudinally extending tubular member 26, which is supported in brackets 27—27 disposed at opposite ends of the corre-

sponding hopper D. Each of said brackets preferably includes a perforated hub section 28 through which the tubular member 26 extends, and above said hub section 28 the bracket is formed with upwardly extending T-shaped flanges, as indicated at 29 and 30, which are connected to the vertical end wall 24 of the adjacent hopper D, and to a bracing gusset H, which extends between the end wall 24 and portions of the car structure as hereinafter pointed out.

At the center of the car, the crossbeam E is given additional depth by means of a flanged diaphragm 31, secured to the lower portion of the transverse beam 25, and extending from the center sill B to the sides of the car. A horizontally extending gusset 32 connects the lower flange of the diaphragm 31 with the center sill. Connected to the opposite sides of the diaphragm 31 are the gussets H which extend to the vertically depending hopper end wall portions 24, and also beneath the sloping floor portions 23, and are securely riveted to all of the said members, and also to the respective flanges 29 and 30 of the brackets 27 as before mentioned. At the extreme ends of the hopper sections, crossbeam members 132 extend outwardly from the center sill to the sides of the car, and are each formed with a flange 33 riveted to the sloping floor portion C. The beams 132, for a limited distance at either side of each wheel, are formed of restricted depth as indicated at 34, to clear the wheels under all conditions of service. A connecting gusset H is also disposed between each of the said beam members 132, and hopper end wall C and connected thereto, and to the flanges 29 and 30 of the adjacent bracket 27. The connecting gussets H, by bracing the hopper vertical end and sloping walls to the transverse beams of the underframe, and in connecting with the brackets 27, serve to rigidify the hopper construction and transmit the strain in a most effective manner from the lower portions of the hoppers to the transverse beams, and thereby to the center sills, and side walls of the car, as will be understood.

As will be especially noted by reference to Figure 2, the side doors F of the respective hoppers when in closed position have their free ends spaced an appreciable distance from the apex of the hopper, and each sloping side of the V-shaped hopper is completed by the lower door G, which is disposed in substantially alignment therewith. Each door G is formed to extend for an appreciable distance beneath its companion door F, when the doors are in closed position, the free end of the door G sloping downwardly and away from the main plane of the door as indicated at 134. Each door G is stiffened longitudinally by means of stiffeners as indicated at 35 and 36, the latter preferably consisting of a Z-bar extended somewhat beyond the ends of the door.

The extreme free edge of the door is rigidified by a marginal flange 234 extending lengthwise of the door.

At each side edge of the door G there is formed a vertically extending wall 37 of generally triangular formation, which effects the double purpose of forming the said door into a pan shape and thereby restricting the flow of material over the ends of the door, and constituting brackets which are pivotally connected with the companion door F by means of bars 38, the pivotal connection of each bar 38 with the bracket being indicated at 39, and with the door F at 40. The connection between the respective adjacent doors F and G is preferably disposed at the ends thereof, the door G being extended beyond the ends of the related door F, and each bar 38 may be disposed between the end of the door F and the inner face of the wall 37 of the corresponding door G when the doors are in closed position, and each bar 38 is pivotally mounted on the door G between a bracket 41 and the wall 37 of the door thereby placing the pivotal connection 39 of the bar 38 in double shear.

Each end of the door F is adapted to extend beneath its adjacent hopper vertical end wall, which is formed in the plane of the said door with a laterally extending flange 42 for the purpose of providing an abutting ledge for the door to fit against when in closed position, said flange 42 beyond the free end of the door merging into the vertical end wall portion of the hopper, thereby preventing material wedging between the ledge and the lower door which would interfere with complete closing movement of said door. The hinge arrangement for each door G preferably consists of a butt hinge arrangement formed of a plurality of longitudinally extending plates 43 formed with hinge eyes, and secured to each of the doors, the hinge portions on the door G on one side of each V-shaped hopper being alternated with the hinge portions on the other door G, associated with the opposite side of the said V-shaped hopper.

The arrangement for raising and lowering the doors includes flexible elements 44 each of which extends at the side edge of its related door G and is connected to the projecting end of the Z-bar 36. Each of said connections is adapted to be engaged by a bracket 45, on the outer side of the wall 37, when the door is in a downwardly inclined position, thereby deflecting the flexible element from the normal straight-line path from the point of its attachment on the door to the point where it is connected to the car structure above the door. This arrangement provides for lifting the door from two different points and affords a differential action which gives an improved angle of pull on the door during the initial stages of the door raising movement, and by providing for an increased length of chain to be taken up in lifting the door, a mechani-

cal advantage is obtained in raising the door and retaining it in a given position under load.

The center doors are adapted to be operated in unison from a single shaft 46 disposed between the center sills, and the outer sets of doors are adapted to be operated independently of each other, and of the center doors, by means of operating shafts 47, one of which is disposed outwardly of the respective hoppers at each side of the car, the flexible connections 44 passing over the pulley wheels 48, mounted adjacent the hopper end walls, and connected to said shafts, the pulley wheels 48 at the ends of the hopper sections, at the center of the car, being mounted on shafts 49, carried in brackets 50 and 51, the former being mounted on the crossbeam diaphragm member 31, and the latter depending from the sloping side walls 23. At the extreme outer ends of the hopper sections, each of said pulley wheels 48 is mounted on a shaft 52 carried by brackets 53 and 54 respectively carried by the sloping walls C and the crossbeam member 132. Secured to each of the respective operating shafts 46 and 47, and as much in alignment with the respective pulley wheels 48 as practicable, are sheave wheels 55, to each of which one end of a flexible connection 44 is secured as indicated at 56. Each flexible connection is adapted to be maintained in engagement with the bracket 45 on the end wall by means of a guide 57 secured to the outer side of the door end wall 37, as shown in Figure 3.

The shaft 46 is adapted to be operated through means of suitable worm and gearing mounted in a casing, as shown conventionally at K, from a cross-shaft 58, extended beyond the respective sides of the car, which has its opposite end portions rotatably mounted in suitable bearings, each bearing being carried by a bracket plate depending from the corresponding crossbeam section 132. Means for rotating and locking the shaft at each end of the shaft is shown conventionally at 61—61, this construction being of a well known form.

The operation of the side doors by means of shaft 47 is effected by means of a short transversely extending shaft 62 having a worm and gear connection with the shaft 47 as best shown conventionally at 63 in Figure 2. Each shaft 62 has an end extended beyond the side of the car and is provided with suitable ratchet mechanism for operating and locking the same as indicated conventionally at 64. The ratchet mechanism 64 is supported from a plate 65 depending from its corresponding side A of the car, and said plate is suitably braced to its adjacent crossbeam section 132. The longitudinal shaft is supported in suitable brackets 66 mounted in the ends of the respective cross-

beam members 31 and 132, as shown in Figure 1.

The combination of the two doors F and G to close a single discharge opening provides for a very large section of sloping floor movable from under the load for the purpose of inducing a ready flow of the lading in the car and preventing arching of the load across the door opening. In cars of the type adapted to be used in ballasting operations it is necessary that the discharging load be always under perfect control of the operator and still issue from the discharge opening in a steady flow, but in order to secure the necessary control of the discharging material to prevent flooding of the rails during ballasting operations it has been customary in certain types of cars to limit the flow of material by providing a very small door opening. In this invention, however, I provide a greater extent of movable floor than has heretofore been used and utilize the upper portions F of such movable floor to restrict the amount of material flowing over the lower portion G of the floor, and thus prevent the free flow of the lading from the car until such time as the member G is inclined to a position below the horizontal plane as indicated in Figure 5 when the flange 234 at the free edge thereof will act as a guard to prevent the heap of ballast adjacent the rail from overflowing the rail. The parts are so arranged that when the ballast commences to flow freely over the edge of the door the heap of ballast sloping from the flange 234 at the swinging edge of the door towards the rail will be below the flange of the wheels, assuming the ballasting material lies at the natural angle of repose for ballasting material.

Assuming the doors to be in closed position and it is desired to ballast between the rails, the operator releases the center door by rotation of the worm and gear through centrally disposed shaft 46, thereby lowering the doors G. As the doors G open, the upper doors F will also open in unison therewith due to the connections 38 between the said respective doors F and G, and until such time as the door G is depressed below the horizontal plane indicated at 67 in Figure 4, the upper door F will prevent free flow of material from the discharge opening. Continued movement of the doors in an opening direction will move the edge of the door to the line indicated at 68 in Figure 5 showing the safe permissible ballast heap adjacent the rail when the slope of the heap of ballast material at the natural angle of repose is below the top of the rail. In order to guard against the possibility of the rail being flooded from an undue flow of material over the side edges thereof the members G are extended an appreciable distance beyond the hopper end walls thereby forming ledges which retain

parts of the overflowing material and in conjunction with the vertical end walls 37 on the doors cause the lading to choke instead of issuing in a steady flow.

5. The closing operation of the doors is the reverse of unloading, the lifting of a door G automatically causing its companion door F to move in advance due to the connecting means between said doors, as will be understood.

15. It will thus be noted that the car is exceedingly simple and that the design provides for a car which will efficiently deposit ballast either centrally of the rails or to the sides thereof.

20. While I have shown and described a specific form of my invention, it will be understood that the same is merely illustrative and I claim all modifications coming within the scope of the appended claims.

25. What I claim is:

1. In a railway car, the combination with a center sill; of hoppers disposed on opposite sides of the center sill, each of said hoppers including means for directing the load either centrally of the rails or to the sides of the track, said directing means including shedding members hinged adjacent the apex of the hoppers; and other movable means forming a portion of the discharge means adapted to restrain the flow of material until the shedding members have been moved to a predetermined position, said other means being terminated position, its lower discharging position controlled by movement of said shedding members.

2. In a railway hopper having one of its sides inclined; a dumping opening formed in said side; a member pivotally mounted adjacent the lower margin of the dumping opening, said member in its upper closed position being adapted to form a portion of the sloping side and in its lower discharging position to form a sloping adjustable shedding member, adapted to determine the plane of ultimate discharge of material directed through the hopper opening; and a second member pivotally mounted adjacent the upper margin of the said opening, said member and said first named member being adapted to complete the sloping side of the hopper, and during discharge of the load being arranged to restrict the flow of material issuing from said dumping opening, movement of said second member being controlled by movement of said first member.

3. In a dump car, in combination with a hopper having an opening extending longitudinally over the rail, a two part closure member for the opening, one of said parts being adapted to form a sloping vertically adjustable shedding member adapted to determine the plane of ultimate discharge of material from the hopper to one side and clear of the rail, and the other of said parts being

adapted to restrict the flow of material passing over the shedding member; and operative connections between the two parts of said closure member whereby operation of one part is automatically controlled by operation of the other.

4. In a dump car, the combination with a hopper having an opening extending longitudinally over the rail; of means for closing said opening and adapted to direct the lading in the hopper to one side or the other of the rail, or to both sides of the rail simultaneously; said means including a two part door member; adapted either to form a portion of a sloping hopper wall or to control the discharge of the lading, said parts when controlling the lading being adapted to separate, one of said parts being adapted to form a shedding member and throw the lading outwardly beyond the rail and the other part being adapted to restrict the flow of lading to the shedding member.

5. In a dump car having a dumping opening extending longitudinally of the car above the rail and substantially midway between the side and longitudinal center of the car, said hopper having side walls sloping downwardly towards each other and forming a substantially V-shaped hopper with the apex approximately over the rail, each side including a fixed upper sloping floor section terminating an appreciable distance from the apex of the hopper; a door pivotally mounted at the terminal edge of each of said fixed floor sections and adapted to continue the plane of the sloping floor beyond the said fixed floor section towards the apex of the hopper, said door when in closed position having the free edge thereof spaced away from the apex of the hopper; doors hinged adjacent the apex of the hopper and adapted to extend upwardly towards the first named doors and to bridge the space between the free edges of said doors and the apex of the hopper; and mechanism for selectively operating said doors whereby the load may be discharged either inwardly or outwardly of the rail.

6. In a dump car, the combination with the center sill, of a V-shaped hopper adjacent the side thereof and adapted to discharge its load centrally over the rail, or to either side thereof, said hopper including fixed sloping side and end wall portions terminating an appreciable distance from the apex of the V-shaped hopper, said fixed sloping sides having the lower margins thereof reinforced by beam members, said hopper end wall being extended below the marginal sloping side walls and formed of a substantially vertically depending section; swinging dumping doors hinged to the said reinforced marginal edge of the sloping side; and a movable member associated with each of said doors adapted to direct the flow of material outwardly be-

yond the free edge of its corresponding door and beyond the rail, said movable member being arranged to supportingly engage its companion door to retain the same in closed position.

7. In a railway car, the combination with a center sill; of V-shaped hoppers disposed on the opposite sides thereof, each of said hoppers having included in one of its sides: a door hinged substantially at the apex of the hopper and a door hinged adjacent its upper edge, the door hinged at the apex of the hopper being extended upwardly and lying beneath the other of said doors when the doors are in closed position; and means connecting said doors whereby they are caused to move in unison.

8. In a dump car, the combination with a V-shaped longitudinally extending hopper disposed substantially above the rail, the lower portion of said hopper being movable to discharge the lading to either one side or the other of the rail or to both sides thereof simultaneously; of vertically disposed end walls adjacent each of said hopper openings, each of said hoppers including a fixed floor portion and a movable side portion, the movable portion comprising two aligned door members, one of said members being in the form of a door hinged below the hopper and the other member comprising a door hinged at its upper end adjacent the lower margin of the fixed floor sloping wall; and connecting means between said aligned doors, said connecting means being disposed adjacent the said hopper vertical end walls outwardly of the hopper.

9. In a dump car, the combination with a V-shaped hopper having included in one of its sides a dump door hinged adjacent the apex of the hopper, said door being movable to an outwardly inclined position; a pulley wheel disposed at the side edge of the door and above the plane of the door; a flexible connection passing over the pulley wheel and connected to the door; and a bracket disposed above the plane of the door adapted to engage with the flexible element when the door is in open position and deflect said flexible element from a straight line path.

10. In a dump car, the combination with a dumping door having an upwardly extending wall adjacent the side edge of the door; of a flexible connection for raising the door extending at the side edge of the door; a pulley wheel disposed above the plane of the door; said flexible connection passing over the pulley wheel and connected to the door; and means on the said wall of the door being adapted as the door opens to deflect the flexible connection from a straight line path intermediate the pulley and the connecting point with the door.

11. In a railway car, the combination with a V-shaped hopper having included in one of

its sloping sides a door hinged adjacent the apex of the hopper, said door when in closed position sloping upwardly and outwardly from the apex of the hopper and movable to a downwardly and outwardly sloping position when in open position; a bracket portion at the end of each door constituting an upwardly extending end wall; a flexible connection connected to the door adjacent each end of the door; a bracket on the said end wall of the door disposed an appreciable distance above the plane of the door and midway between the hinged end and the free end of the door, said bracket when the doors are fully opened being adapted to engage with the flexible connection above its point of connection with the door and increase the length of flexible connection to be taken up to raise the door.

12. In a railway car the combination with a center sill, of a hopper on each side thereof, each of said hoppers having sloping side and end walls, said end walls having vertically depending end portions of triangular shape, the sloping side walls adjacent said vertical end walls of each hopper being movable to discharge the load either centrally between the rails or to the outer sides thereof, each of said movable walls of each hopper being composed of two hinged portions, one of said portions being pivoted below the hopper and the other portion being pivoted at its upper end adjacent the lower margin of the sloping fixed floor portion, said lower portion having an upwardly vertically extending wall at each end thereof adapted to lie adjacent its corresponding end wall when the movable floor is in closed position; and a connection between each of said end walls of the lower door and its companion upper door, whereby the said respective upper and lower doors are caused to move in unison.

13. In a railway car, a V-shaped hopper having one of its sides composed of a door hinged adjacent its upper edges and a door hinged adjacent the apex of the hopper, said last named door having flanges at the sides thereof adapted to lie adjacent the sides of the other door when said doors are in closed position.

14. In a railway car, a longitudinally extending hopper extending above the rail, said hopper being in the form of a V-shape and having both sides thereof movable to discharge to either side of the rail or to both sides thereof simultaneously, each of said sides including a door hinged adjacent the apex of the hopper and a companion door in alignment therewith, said first named door having side walls at either side thereof extending upwardly above the plane of the door thereby providing a pan shape effect, said pan shaped door when in closed position being adapted to enclose its companion door.

15. In a railway car, the combination with a hopper having an opening for the purpose of discharging ballast; of means for controlling the discharge of said ballast and directing the same outwardly beyond the rail, said means including a pivotally mounted door having the side edge extending beyond the end of the hopper opening and forming a ledge projecting at each end of the hopper; and additional means for the purpose of restricting the flow of ballast over the rail at the side of the door, said means comprising an upwardly extending wall rising above the swinging member at the side edge of the door.
16. In a railway car, the combination with a hopper having an opening; of means for directing ballast away from said opening and beyond a rail, said means including a pivoted member extending beyond the end of the hopper opening whereby a load sustaining ledge is provided for an appreciable distance beyond the end of said hopper and an undue flow of material over the edge of the door is thereby prevented.
17. In a railway car, a longitudinally extending hopper having a sloping side, the lower portion of said side having a dumping opening therein; a closure for the said opening, said closure being formed of two doors, one of said doors being pivoted adjacent one side of the dumping opening and the other of said doors being pivoted adjacent the opposite side of the dumping opening, one of said doors being extended beneath the other of said doors, the door extending beneath the other having the outer end thereof deflected outwardly and downwardly from said other door.
18. In a railway car, the combination with a V-shaped hopper having at each end a vertically depending end wall; of a plurality of doors hinged on a common pivot; said doors extending upwardly and outwardly from the apex of the hopper to form a portion of the floor of the car, and movable to a downwardly and outwardly inclined position to discharge lading; a bracket member at each end of the hopper secured to each vertical end wall of the hopper; a beam extending in parallelism with the vertical end wall of the hopper and spaced therefrom; a spacing member extending between said beam and the vertical end wall of the hopper and secured to both of said members and also to the bracket member; and a door supporting member extending between and carried by the bracket members at the respective ends of the door.
19. In a dump car, the combination with a centersill; of a longitudinal hopper disposed to one side of the centersill adapted for discharge to either one side or the other of the rail, said hopper having sloping side and end walls, the end wall having a vertically depending portion; a beam member extending adjacent each hopper vertical end wall and connecting the centersill and the side wall, each of said beams being disposed beneath the sloping end wall of the hopper; bracing means between the hopper vertical end wall portion and the beam; and a door raising connection interposed between said hopper end wall and the beam adjacent thereto.
20. In a dump car, the combination with the centersill and side walls of the car; of a hopper disposed on each side of the centersill, each of said hoppers being adapted for discharging the load centrally between the rails or to the outer side thereof; and supporting means for each of said longitudinal hoppers comprising a cross-beam disposed at the end of each hopper and extending from the centersill to the side wall of the car and supported thereby, and a gusset extending from said cross beam to the end wall of its corresponding hopper and secured thereto.
21. In a dump car, the combination with a centersill and the side wall thereof; of a longitudinally extending hopper disposed intermediate said centersill and side wall; a beam member disposed beneath the end of the hopper and spaced an appreciable distance from the end of the hopper opening; a bracing connection between said beam and the end hopper wall, said beam having a portion thereof formed of restricted depth intermediate the ends thereof in order to clear the wheel of the car; and door raising means carried by the hopper end wall and said beam.
22. In a dump car, the combination with the center sill and the side walls of the car; of a hopper disposed on each side of the centersill, each of said hoppers being adapted for discharging the load centrally between the rails or to the outer side thereof; supporting means for each of said longitudinal hoppers comprising: a series of cross-beams disposed at the end of each hopper and extending from the centersill to the side wall of the car and supported thereby, a gusset extending from each of said cross-beams to the end of the corresponding hopper and secured thereto, each said gusset having a portion depending below its corresponding cross-beam; hinge brackets secured to the depending portion of the gusset and to the end wall of the hopper; a door supporting member carried by said hinge brackets; and doors mounted upon said supporting members for closing the hopper opening.
23. A dump car having a hopper including an upper fixed inclined floor section with a discharge opening therebelow, a pair of hinged members for closing said opening, one of said members being hinged along its upper edge and the other along its lower edge, said member pivoted at its lower edge acting as a shedding member when in open position and adapted to vary the plane of ultimate discharge of material and the other

member acting as a restraining member for the load during opening movements of said members, and operating means for said members to synchronize opening movements thereof and restrain the discharge of the load until said member pivoted at its lower edge reaches a predetermined downward slope.

24. In a dump car having a hopper section with a discharge opening therein, the combination with two doors for closing said opening, the upper door being pivoted along its upper edge and the lower door pivoted along its lower edge, the lower door being of greater width than the upper door and overlapping the latter when in closed position, both of said doors being in an inclined position when closed; of means controlling the opening movement of the upper door during the opening movement of the lower door so as to maintain a relatively narrow opening between the upper door and the lower door until the latter has swung to a position inclined downwardly from a horizontal plane.

25. A dump car having a hopper including opposed oppositely inclined upper fixed floor sections with discharge openings therebelow, a pair of hinged members for closing each of said openings, one of said members of each pair being hinged along its upper edge and the other hinged along its lower edge, each said member pivoted at its lower edge acting as a shedding member when in open position and adapted to vary the plane of ultimate discharge of material and the co-operating other member acting as a restraining member for the load during the opening movements of each pair of said members; and operating means for each pair of said members to synchronize the opening movements thereof and to restrain the discharge of the load until said member of each pair that is

pivoted at its lower edge reaches a predetermined downward slope.

26. In a dump car having a hopper section of V-form and two dumping openings on opposite sides of the apex thereof, the combination with an upper door pivoted at its upper edge and a lower door pivoted at its lower edge for closing each of said openings, each lower door being of greater width than its corresponding upper door and overlapping the latter when in closed position; and means controlling the opening movement of the upper door of each pair, during the opening movement of the corresponding lower door so as to maintain a relatively narrow opening between the upper door and lower door of each pair until the lower door has swung to a position inclined downwardly from a horizontal plane.

27. A dump car having a longitudinally extending hopper section on each side of the center sill, each hopper section including oppositely inclined upper fixed floor sections with oppositely arranged openings therebelow; means for closing each of said openings, each said means comprising an upper door and a lower door, the former pivoted along its upper edge and the latter pivoted along its lower edge; and mechanism for selectively operating each pair of doors, whereby the load may be dumped either inwardly or outwardly of the rails or both, said mechanism including, for each pair of doors, means for synchronizing the opening movements thereof and to restrain the discharge of the load until the lower door of the pair reaches a predetermined downward slope.

In witness that I claim the foregoing I have hereunto subscribed my name this 22nd day of May, 1925.

GEORGE BINET DOREY.
